UNITED STATES PATENT OFFICE

LYALL DOUGLAS STEWART, OF TE KUITI, NEW ZEALAND

ELECTRIC-WIRE CONNECTER

Application filed September 23, 1927. Serial No. 221,542.

This invention relates to devices of the type used for connecting wires from one line to another, as in electric wiring circuits or the like.

Devices for this purpose are known, but they have the disadvantage that only two wires can be housed in the connector at one time, whereas with my invention, two or more wires of the same or of different diameters may be clamped or connected as desired.

In previous devices of a similar nature to my present invention, a serious disadvantage to workers engaged on live wire reticulation is that the separate parts comprising the connectors all have to be controlled by hand while clamping the wires in position, and this disadvantage will be obvious, especially in regard to work taking place at a height. Therefore I have devised an improvement on such known devices and the object of the present specification is to indicate such improvements in the constructural features of my invention.

In the drawings accompanying this specification:—

Figure 1 is a perspective view of my invention.

Figure 2 is a sectional elevation of same.

Figure 3 is a perspective view of a further type of my invention.

Figure 4 is a view of the main body portion of the connector.

Figures 5 and 6 are views of other parts comprising the invention.

Broadly my improved device comprises a solid main body portion 1 of any desired size and material, the surface of which is tinned to prevent corrosion.

In one form of my invention designed to house a main electric cable lead 2 of any size, and three secondary circuit wires 3, the said body portion consists of a solid member provided with upper and lower flat surfaces 4 and 4A in which are grooves 5 and 5A the upper surface or bed 4 being provided with two sides or lugs 6 which are formed at right angles to the said surface 4, and the lower surface or bed 4A is fashioned in a similar manner as at 7, the construction thus forming continuous and retaining side walls for the

electric wires 2 and 3 and clamping pieces 8 and 9 positioned in relation to said body portion 1.

Solid with the main body portion 1, and projecting upwardly and downwardly therefrom are bolt members 10 and 10A of any convenient size, threaded at each end for any desired length with a right and left hand thread. The purpose of these bolt members 10 and 10A is to retain suitably shaped clamping pieces 8 and 9 which are provided preferably with a central slot 11, and have their inner-surfaces grooved as at 12 to correspond with the grooves 5 and 5A on the upper and lower surfaces 4 and 4A of the main body portion 1, so as to lie on the round surface of the electric wires, thus embedding the whole of the wires within the said grooves, see Figure 2.

It will be understood that the clamping pieces 8 and 9 fit over the upper and lower surfaces 4 and 4A of the said main body portion 1, and between the lugs 6 forming the sides of the device.

Both upper and lower clamping pieces 8 and 9 may overlap the surface of the main body portion 1 with the object of permitting a greater surface contact for the wires housed therein.

In the event of having to tap a large main with a smaller secondary or service lead, I provide an auxiliary clamping piece 14, with a projection 13 on one side of it (see Figures 2 and 6). The purpose of this construction is to take the strain off the threaded bolt and present a flat surface to the nut when being screwed down on the clamping piece.

The auxiliary member 14 is of wedge-shaped construction, centrally slotted as at 15 and adapted to be passed over the threaded bolt 10 with the projecting portion 13 uppermost or underneath as may be required.

In a device for a two-wire connection, the construction is slightly different, in that the main body portion 1 is provided with upwardly disposed right angle lugs 15 and 15A and only one bed and set of grooves 16, while the undersurface of the body is tapered to a V-shaped form, as at 17 the purpose of which is to provide either a finger or plier grip for

use when tightening up or loosening the connector.

A threaded bolt 18 solid with the body 1 is also provided, and also one clamping piece 19 overlapping the body portion together with its retaining washer 20 and nut 21. In both cases for keeping the clamping pieces in position, spring washers 20 are provided and kept in position on said threaded bolt adjacent the flat surface of said clamping pieces by means of nuts 21.

When using my invention to clamp or connect wires from one line to another, or from a main lead, the parts constituting the invention are assembled as follows:—

First, the main body member is taken and in one side groove thereof the main lead is laid, and on the other side a secondary wire or house connection; the clamping piece is now placed over the threaded bolt and the washer and nut screwed thereon making firm contact; thus the connector holds itself in position to allow the other lead wires being placed in position on the other bed or surface of the body portion, and to be retained therein by means of the second clamping piece and its washer and nut.

During dismantling, the secondary wires may be taken separately or collectively from the connector without uncoupling the whole device from the main lead. This operation cannot be accomplished by any other connector.

A further advantage of my connector lies in the fact that no two wires come in actual contact with one another, thus avoiding any danger of corrosion, due to the chemical action caused by adjacent copper surfaces.

What I claim as new and desire to secure by Letters Patent is:—

1. A connection clamp for wires comprising a body portion formed at one end with a recess to provide depending legs, a centrally disposed screw extending from the body portion and beyond the ends of the legs, a tiltable plate fitting within the recess and provided with an elongated opening through which the screw passes, means on the screw for engaging the plate to clamp wires in the recess between the plate and the body portion, the opposite end of the body portion having a recess to provide a second pair of legs, a screw extending from said opposite end and beyond said second pair of legs, a plate having an opening through which said second mentioned screw extends to clamp wires between the second set of legs.

2. A connection clamp for wires, comprising a body portion having at one end a pair of legs, a centrally disposed screw extending beyond the plane of the ends of said legs, a tiltable plate fitting in the recess and provided with an elongated recess through which the screw passes, the plate having depressions of various depths, the adjacent face of the body

portion having corresponding depressions, an auxiliary clamping plate formed with an opening for the passage of the screw and fitted under the first mentioned plate, said second mentioned plate having an enlargement on one face to engage the first mentioned plate when tilted due to clamping wires of different diameters, and a nut on the screw to force the plates together to clamp the wires against the body portion.

In testimony whereof I affix my signature.

LYALL DOUGLAS STEWART.
